SWITCH CONTROL AND INDICATION
SYSTEMHenry S. Young, Wilkinsburg, Pa., assignor to
The Union Switch & Signal Company, Swiss-
vale, Pa., a corporation of Pennsylvania

Application March 31, 1939, Serial No. 265,257

12 Claims. (Cl. 246—219)

My invention relates to an improved system for controlling the motor for operating a railway track switch and for providing an indication of the position occupied by the switch.

It has recently been proposed to provide interlocking systems employing relays exclusively instead of the mechanically interconnected control apparatus heretofore employed, and this control system is designed particularly for use in all relay type interlocking installations.

It is also proposed to employ in interlocking systems of the kind referred to above relays of the plug-in type, that is, relays having contact pins or sockets which are adapted to be detachably received by cooperating contact sockets or pins carried by a base member which is permanently secured to a support and to which connections are made for the conductors forming the circuits controlled by the relay contacts. Plug-in type relays are advantageous as the relays may be readily removed and replaced for servicing or for inspection, while a relay of this type may be quickly and easily replaced by another if desired.

Unless some means is provided to prevent such an occurrence, vibrations, such as caused by passing trains, may, when the relay armature is released, produce such movement of the relay armature as to cause the back contacts of the relay, that is, the contacts which are closed when the relay armature is released, to become open, while the armature may move sufficiently to effect closing of the relay front contacts.

It has heretofore been proposed to provide cushioning or shock absorbing means to protect relays from vibration of this kind, but the construction and mounting of plug-in type relays is such that it is difficult or impractical to employ cushioning means to protect them. Accordingly it has been proposed to incorporate in such relays a permanent magnet which serves to hold the relay armature in its released position and to prevent movement of the armature from the released position as a result of vibration. A relay incorporating the permanent magnet hold-down feature is responsive to energization of its winding with current of one relative polarity only.

A relay of this type which may be employed in the system shown in this application is shown in United States Patent No. 1,959,562, issued May 22, 1934, to Harry E. Ashworth.

It is an object of my invention to provide a switch control system employing relays of a type having a permanent magnet for normally

maintaining the relay armature in its released position.

A further object of my invention is to provide an improved switch control system adapted for use in all relay types of interlocking installations.

Another object of my invention is to provide an improved switch control system employing relays of the type having a permanent magnet to maintain the relay armature in its released position, the system being adapted for use in all relay types of interlocking installations.

Another object of my invention is to provide an improved switch control system employing relays which are responsive to current of one polarity only instead of the polarized relays heretofore employed which are selectively responsive to current of opposite relative polarity.

A further object of my invention is to provide a switch control system employing a normal and a reverse control relay operative when energized to effect movement of the switch to its normal or reverse positions, respectively, the system being arranged so that on energization of the winding of either control relay a circuit is established to maintain the winding of that control relay energized until the winding of the other control relay is energized to thereby insure that when the switch is moved to one of its positions, it will remain in that position until it is intentionally moved therefrom.

Another object of my invention is to provide an improved switch control and indication system.

Other objects of my invention and features of novelty will be apparent from the following description taken in connection with the accompanying drawings.

I shall describe four forms of apparatus embodying my invention, and shall then point out the novel features thereof in claims.

In the drawings,

Fig. 1 is a diagram showing one system embodying the improved switch control and indication system provided by my invention,

Fig. 2 is a modified form of system embodying my invention,

Fig. 3 is a further modification which I may employ, and

Fig. 4 is still another modification which I may employ.

In the system shown in Fig. 1, as well as in other figures of the drawings, the switch W may be but one of several switches of a group of switches which may be selectively operated

to provide a plurality of different routes through the location in which the switches are situated.

Referring to Fig. 1 of the drawings, the reference character W designates a railway track switch which is movable between a normal and a reverse position by a suitable motor, here shown as a pneumatic motor.

The supply of fluid under pressure to the motor is controlled by a lock magnet valve device LMV, a normal magnet valve device NMV and a reverse magnet valve device RMV.

The magnet valve devices associated with the motor control the supply of fluid under pressure thereto in the usual manner. The lock magnet valve device LMV is operative when energized to permit the supply of fluid under pressure to the motor, and when deenergized to cut off the supply of fluid under pressure to the motor.

The normal magnet valve device NMV is operative when energized to direct the flow of fluid under pressure supplied through the lock magnet valve device LMV to effect operation of the motor to cause movement of the switch W to the normal position, while the reverse magnetic valve device RMV is operative when energized to direct the flow of fluid under pressure supplied through the lock magnet valve device LMV to cause operation of the motor to move the switch W to the reverse position.

The circuits of the windings of the magnet valve devices are controlled by a normal control relay WNR, a reverse control relay WRR, and by the normal and reverse switch indication or switch repeating relays NWPR and RWPR, respectively. The supply of current to the windings of the switch indication or switch repeating relays is controlled by contacts 10 and 11 which are movable in accordance with movement of the switch W.

The circuit for energizing the winding of the normal control relay WNR is controlled by a normal push button stick relay NPBSR, by a normal route relay NRR, and by a lock relay LR.

Similarly, the circuit of the winding of the reverse control relay WRR is controlled by a reverse push button stick relay RPBSR, by a reverse route relay RRR, and by the lock relay LR.

The pick-up and stick circuits for the normal and reverse push button stick relays are controlled by normal and reverse push buttons NPB and RPB, respectively, while the stick circuit for each of these relays is also controlled by a contact of the relay as well as by a contact of the other one of the stick relays. In addition, the circuits of the windings of the push button stick relays are controlled by a contact of the lock relay LR to prevent energization of either of the stick relays at a time when the lock relay is deenergized to thereby prevent storage of switch control.

The circuit of the winding of the normal route relay NRR is controlled in any suitable manner by means not shown so that the relay winding is energized when and only when a route is established which includes the switch W in the normal position.

Similarly, the circuit of the winding of the reverse route relay RRR is controlled in any suitable manner by means not shown so that the relay winding is energized when and only when a route is established which includes the switch W in the reverse position.

The control of the circuits of the windings of the normal and reverse route relays NRR and RRR is not a part of this invention, and any

suitable means well known in the art may be employed for the purpose.

Similarly, the control of the circuit for energizing the winding of the lock relay LR does not form a part of this invention, and this circuit may be controlled in the manner well known in the art so that the relay winding is energized when and only when it is safe to effect movement of the switch W between its two positions.

One form of apparatus for controlling the supply of energy to the windings of the route relays NRR and RRR and to the winding of the lock relay LR is shown in application Serial No. 118,609, filed December 31, 1936, by John M. Pelikan.

The normal and reverse control relays WNR and WRR, the normal and reverse indication relays NWPR and RWPR, and the lock relay LR are of the type having a permanent magnet to aid in maintaining the relay armature in its released position.

The normal and reverse push buttons NPB and RPB are of the type having a movable member which is biased to an intermediate position, while the movable member is moved in one direction from this position when pressure is applied to the push button knob and is moved in the other direction from this position when the knob is pulled.

The normal push button NPB has a normally open contact 12 which engages contact 13 when pressure is applied to the knob of the push button. This push button also has normally closed contacts 24 and 25 which become open when the knob of the push button is pulled.

Similarly, the reverse push button RPB has a normally open contact 32 which engages contact 33 when pressure is applied to the knob of the push button, while this push button also has normally closed contacts 38 and 39 which become open when the knob of the push button is pulled.

The switch operated contacts 10 and 11 control supply of current and also the polarity of the current supplied to supply wires for energizing the switch indication or switch repeating relays NWPR and RWPR, while the normal and reverse control relays WNR and WRR control the circuits of the windings of the relays NWPR and RWPR.

The contact 10 has wire 15 connected thereto, while contact 11 has wire 20 connected thereto. The contacts 10 and 11 are arranged so that contact 10 engages a stationary contact 102 and the contact 11 engages a stationary contact 103 when and only when the switch W is in the normal position. Similarly, the contacts 10 and 11 are arranged so that the contact 10 engages a contact 97 and the contact 11 engages contact 102 when and only when the switch W is in the reverse position.

While the contacts 10 and 11 have been described as engaging the associated stationary contacts when the switch W is in one position or the other, it should be understood that these contacts may be arranged in the manner well known in the art so that the circuits controlled thereby will be complete when and only when the switch not only is in one position or the other, but is also locked in that position.

The contact 102 has supply wire 104 connected thereto, while contacts 97 and 103 have supply wire 105 connected thereto.

It will be seen that when the switch W is in one position, current of one relative polarity is supplied from wires 15 and 20 through the con-

acts 10 and 11 to the supply wires 104 and 105, while in the other position of the switch W current of the opposite or reverse relative polarity is supplied to the wires 104 and 105.

As previously pointed out, the relays NWPR and RWPR are of a type which incorporate a permanent magnet to secure their armatures in their released positions and are responsive to current of one relative polarity only. The various parts of this system are arranged so that the contacts of the normal indication relay NWPR become picked up only when the relay winding is energized with current of the polarity which is supplied to the supply wires 104 and 105 in the normal position of the switch W. Similarly, the contacts of the reverse indication relay RWPR become picked up only when the relay winding is energized with current of the polarity which is supplied to the wires 104 and 105 in the reverse position of the switch W.

The supply wire 104 is connected to one terminal of the windings of the relays NWPR and RWPR, while supply wire 105 is connected to contact 107 of relay WNR, and also to contact 108 of relay WRR. Contact 107 when released engages contact 109 which is connected by wire 110 to a terminal of the winding of relay RWPR, while contact 108 when released engages contact 112 which is connected by wire 113 to a terminal of the winding of relay NWPR.

Thus it will be seen that the circuit of the winding of the reverse indication relay RWPR is complete only when the contacts of the normal control relay WNR are released, and that the circuit of the winding of the normal indication relay NWPR is complete only when the contacts of the reverse control relay WRR are released.

The indication relays NWPR and RWPR have contacts other than those shown in the drawings for controlling the signals, not shown, which are associated with the switch W. The control of the signals may be effected in any suitable manner well-known in the art.

Similarly the indication relays NWPR and RWPR may be provided with contacts, not shown, and controlling circuits which control indication means, not shown, for indicating at a remote point, as for example at the point at which the push buttons NPB and RPB are located, the position occupied by the switch W.

The equipment is shown in the drawings with the switch W in the normal position and with the lock relay LR, the normal control relay WNR, and the normal indication relay NWPR energized. The equipment is also shown with the normal and reverse route relays NRR and RRR deenergized.

At this time the winding of the relay WNR is energized by current supplied over the stick circuit established by its own contact. This circuit is traced from terminal B of battery 16 through wire 15, contacts 71-66 of relay WNR, wire 67, contacts 68-73 of relay WRR, wire 52, winding of relay WNR and wire 20 to terminal C of battery 16.

As the winding of relay WNR is energized, the contacts of this relay are picked up and contact 77 of the relay engages contact 80 and establishes connection from wire 81 to wire 75 leading to the winding of the lock magnet valve device LMV. However, at this time, as explained below, contact 83 of relay NWPR is picked up and no connection is established from the wire 15 to wire 81, and accordingly the winding of

the lock magnet valve device LMV is not energized. Since the lock magnet valve device LMV is not energized, this valve device prevents the supply of fluid under pressure to the switch motor.

At this time the winding of normal indication relay NWPR is energized from the supply wires 104 and 105 over a circuit established by contact 108 of relay WRR. This circuit is traced from wire 105 through contacts 108-112 of relay WRR, wire 113, winding of relay NWPR and wire 104.

At this time as the switch W is in the normal position, the contacts 10 and 11 effect the supply of current from wires 15 and 20 to wires 104 and 105 of a polarity effective to cause picking up of the contacts of relay NWPR.

As the normal control relay WNR is energized and as the relays WRR and RWPR are not energized, a circuit is established to energize the winding of normal magnet valve device NMV. This circuit is traced from terminal B of battery 16 through wire 15, contacts 90-88 of relay RWPR, wire 86, contacts 99-98 of relay WRR, wire 96, contacts 94-93 of relay WNR, wire 92, winding of magnet valve device NMV, and wire 20 to terminal C of battery 16.

As the winding of the lock magnet valve device LMV is deenergized, the normal magnet valve device NMV, even though energized, is ineffective to supply fluid under pressure to the motor for the switch W. However, if the switch W should creep from the normal position, contacts 10 and 11 will be moved out of engagement with contacts 102 and 103, thereby interrupting the circuit for energizing the winding of relay NWPR with the result that contact 83 of relay NWPR will become released and will complete the circuit of the winding of the lock magnet valve device LMV. The circuit for energizing the lock magnet valve device LMV at this time is traced from terminal B of the battery 16 through wire 15, contacts 83-82 of normal indication relay NWPR, wire 81, contacts 80-77 of normal indication relay WNR, wire 75, winding of lock magnet valve device LMV, and wire 20 to terminal C of the battery 16.

On energization of the winding of the lock magnet valve device at a time when the winding of the normal magnet valve device NMV is energized, fluid under pressure is supplied to the switch motor to cause the motor to return the switch W to the normal position. When the switch reaches the normal position, contacts 10 and 11 again establish the circuit for energizing the winding of the relay NWPR, while the contact 83 becomes picked up and interrupts the circuit of the lock magnet valve device LMV which thereupon operates to cut off the supply of fluid under pressure to the switch motor.

If at this time the operator desires to effect movement of the switch W from the normal to the reverse position, he may do so by applying pressure to the knob of the push button RPB. This will close contacts 32 and 33, thereby completing the pick-up circuit for the winding of relay RPBSR. This circuit is traced from terminal B of battery 16 through push button contacts 32-33, wire 34, winding of relay RPBSR, wire 35, contacts 36-37 of relay NRR, wire 21, contacts 22-23 of relay LR, and wire 20 to terminal C of battery 16. Accordingly contacts 30, 41 and 56 of relay RPBSR become picked up and contact 41 establishes a stick circuit for the winding of this relay. This circuit is traced from

wire 15 through contacts 39—38 of push button RPB, wire 40, contacts 41—42 of relay RPBSR, wire 43, contacts 45—44 of relay NPBSR, wire 34, winding of relay RPBSR, wire 35, contacts 36—37 of relay NRR, wire 21, contacts 22—23 of relay LR, and wire 20 to terminal C of battery 16.

It will be seen that the pick-up and stick circuits for the relay RPBSR include a contact of the normal route relay NRR and a contact of the lock relay LRR so that the relay RPBSR can be energized only when the contacts of the normal route relay are released and the contacts of the lock relay are picked up. This insures that the relay RPBSR can be energized only when it is safe to effect movement of the switch to the reverse position.

Contact 56 of relay RPBSR, when picked up, completes the pick-up circuit for the winding of the reverse control relay WRR provided the contacts of the reverse route relay RRR are released. This circuit is traced from terminal B of battery 16 through wire 15, contacts 56—57 of relay RPBSR, wire 58, contacts 59—60 of relay RRR, wire 62, contacts 63—64 of relay LR, wire 65, winding of relay WRR and wire 20 to terminal C of battery 16.

It will be seen that on picking up of the contacts of relay RPBSR, contact 30 of the relay interrupts the stick circuit for the winding of relay NPBSR to thereby deenergize the winding of this relay if it is maintained energized by current supplied over its stick circuit.

Since the circuit controlled by the relay RPBSR for energizing the reverse control relay WRR includes a back contact of the reverse route relay RRR, this circuit can be established only if the contacts of the relay RRR are released. If the contacts of the relay RRR are picked up, the relay WRR will be energized by current supplied over the circuit which is traced from terminal B of battery 16 through wire 15, contacts 61—60 of relay RRR, wire 62, contacts 63—64 of lock relay LR, wire 65, winding of relay WRR, and wire 20 to terminal C of battery 16.

On energization of the winding of the reverse control relay WRR and picking up of the contacts of this relay, contact 68 becomes picked up and interrupts the previously traced stick circuit for the winding of the normal control relay WNR. On picking up of contact 68 it engages contact 74 to which is connected a branch of wire 15, while on deenergization of the winding of normal control relay WNR, its contact 66 becomes released and engages contact 70 to establish the stick circuit for the winding of reverse control relay WRR. This circuit is traced from wire 15 through contacts 74—68 of relay WRR, wire 67, contacts 66—70 of relay WNR, wire 65, winding of relay WRR and wire 20.

On picking up of contact 198 of relay WRR the circuit of the winding of relay NWPR is interrupted and contact 83 of this relay becomes released to establish connection from wire 15 to wire 81.

On deenergization of the winding of relay WNR and release of the contacts of this relay, contact 94 of the relay becomes released to thereby interrupt the circuit of the winding of the normal magnet valve device NMV, and to establish connection from wire 81 to wire 96, while on picking up of contact 98 of relay WRR connection is established from wire 96 to wire 101 leading to the winding of the reverse magnet valve device RMV. The circuit for energizing the winding of magnet valve device RMV is now

complete and is traced from wire 15 through contacts 83—82 of relay NWPR, wire 81, contacts 95—94 of relay WNR, wire 96, contacts 98—100 of relay WRR, wire 101, winding of magnet valve device RMV, and wire 20.

On release of contact 107 of relay WNR the circuit for energizing the winding of relay RWPR from the wires 104 and 105 is complete, but at this time, as the switch W is still in the normal position, the polarity of the current supplied to the wires 104 and 105 is not that which is effective to cause picking up of the contacts of relay RWPR, but instead is that which is effective to cause the contacts of the relay to be held in their released position with greater than usual force. Accordingly contact 90 of relay RWPR is in engagement with contact 88 at the time that contact 78 of relay WRR becomes picked up, and on picking up of contact 78 the circuit for energizing the lock magnet valve device LMV is complete. This circuit is traced from wire 15 through contacts 90—88 of relay RWPR, wire 86, contacts 85—78 of relay WRR, wire 75, winding of lock magnet valve device LMV, and wire 20.

As both the lock magnet valve device LMV and the reverse magnet valve device RMV are energized, fluid under pressure is supplied to the motor for the switch W to effect movement of the switch W to the reverse position. On movement of the switch W away from the normal position contacts 10 and 11 are moved out of engagement with the stationary contacts associated therewith, thereby interrupting the supply of current to the supply wires 104 and 105. On the resultant deenergization of the winding of relay RWPR the contact 90 of this relay remains in engagement with contact 88, being held in engagement therewith by gravity and by the permanent magnet incorporated in the relay.

When the switch W attains the reverse position, contact 10 engages contact 97 and contact 11 engages contact 102, thereby effecting the supply of current from wires 15 and 20 to supply wires 104 and 105 of a polarity effective to cause picking up of contact 90 of relay RWPR. When the contact 90 of relay RWPR is picked up, it interrupts the circuit for energizing the lock magnet valve device LMV, and this valve device thereupon operates to prevent further supply of fluid under pressure to the motor for the switch W.

At this time the winding of the reverse magnet valve device RMV continues to be energized over the previously traced circuit so that in the event the switch W creeps from its reverse position, and the lock magnet valve device LMV becomes energized, fluid under pressure will be supplied to the switch motor to return the switch to the reverse position.

In the event the switch W does creep from the reverse position contacts 10 and 11 will be moved out of engagement with the stationary contacts associated therewith, thereby interrupting the circuit for energizing the winding of relay RWPR and the contact 90 of this relay will become released to reestablish the circuit of the winding of the lock magnet valve device LMV. As soon as the switch W is returned to the reverse position, contacts 10 and 11 will again effect the supply of current to the supply wires 104 and 105 and contact 90 of relay RWPR will become picked up and will interrupt the circuit of the winding of the lock magnet valve device.

If on movement of the switch W to the reverse position the operator wishes to release the contacts of the relay RPBSR, he may do so by pull-

ing on the knob of the push button RPB. This opens the contacts 38 and 39 and interrupts the stick circuit for the winding of the relay RPBSR. Accordingly the contacts 30, 41 and 56 of this relay become released. On opening of contact 56 the pick-up circuit for the winding of reverse control relay WRR is interrupted, but the winding of this relay continues to be energized by current supplied over the stick circuit for the relay winding which was established on picking up of its own contact 68 and on release of contact 66 of relay WNR. Accordingly, the contacts of relay WRR continue to be picked up and maintain the previously traced circuit for the reverse magnet valve device RMV and the lock magnet valve device LMV.

If while the switch W is in the reverse position the operator desires to effect return of the switch to the normal position, he may do so by pressing on the knob of the normal push button NPB. This closes the contacts 12-13 of the push button, and, assuming that the contacts of reverse route relay RRR are released and that the contacts of the lock relay LR are picked up, completes the pick-up circuit for the winding of the relay NPBSR. This circuit is traced from terminal B of the battery 16 through wire 15, contacts 12-13 of the normal push button NPB, wire 14, winding of relay NPBSR, wire 17, contacts 18-19 of reverse route relay RRR, wire 21, contacts 22-23 of lock relay LR, and wire 20 to terminal C of battery 16. The contacts of relay NPBSR accordingly become picked up and contact 46 of the relay interrupts the stick circuit of the winding of relay RPBSR if it is not already interrupted by contact 41 of relay RPBSR. In addition, on picking up of contact 28 of relay NPBSR the stick circuit for the winding of this relay is established, while on picking up of contact 46 of the relay NPBSR the circuit for energizing the winding of the normal control relay WNR is complete.

The stick circuit for the winding of relay NPBSR is traced from wire 15 through push button contacts 25-24, wire 26, contacts 27-28 of relay NPBSR, wire 29, contacts 30-31 of relay RPBSR, wire 14, winding of relay NPBSR, wire 17, contacts 18-19 of relay RRR, wire 21, contacts 22-23 of lock relay LR, and wire 20.

The circuit for energizing the winding of normal control relay WNR is traced from wire 15 through contacts 46-47 of relay NPBSR, wire 48, contacts 49-50 of relay NRR, wire 53, contacts 54-55 of relay LR, wire 52, winding of relay WNR to wire 20.

Since the circuit controlled by the relay NPBSR for energizing the normal control relay WNR includes a back contact of the normal route relay NRR, this circuit can be established only if the contacts of the relay NRR are released. If the contacts of the relay NRR are picked up, the relay WNR will be energized by current supplied over the circuit which is traced from terminal B of battery 16 through wire 15, contacts 51-50 of relay NRR, wire 53, contacts 54-55 of relay LR, wire 52, winding of relay WNR, and wire 20 to terminal C of battery 16.

On energization of the winding of relay WNR the contacts of this relay become picked up and when contact 66 is picked up, it interrupts the stick circuit for the winding of reverse control relay WRR and the contacts of relay WRR become released.

On release of the contacts of reverse control relay WRR, contact 68 is moved into engagement

with contact 13 to thereby complete the stick circuit for the winding of relay WNR.

This circuit is traced from wire 15 through contacts 71-66 of relay WNR, wire 67, contacts 68-73 of relay WRR, wire 52, and winding of relay WNR to wire 20. Accordingly when the contacts of relay WNR become picked up, they will thereafter remain picked up until the winding of reverse control relay WRR is energized and effects picking up of the contacts of that relay.

On picking up of the contact 107 of relay WNR the circuit for energizing the winding of relay RWPR is interrupted and contact 90 of relay RWPR becomes released.

On release of contact 90 of relay RWPR connection is established from wire 15 to wire 86, while on release of contact 98 of relay WRR connection is established from wire 86 to wire 96. In addition, on picking up of contact 94 of relay WNR connection is established from wire 96 to wire 92 leading to the winding of the normal magnet valve device NMV, and this winding thereupon becomes energized.

At this time as the switch W is in the reverse position, current is supplied through contacts 10 and 11 to the wires 104 and 105, while on release of contact 103 of relay WRR the circuit for energizing the winding of relay NWPR from the wires 104 and 105 is complete. However, the polarity of the current supplied to the wires 104 and 105 at this time is such that the current is ineffective to cause picking up of contact 83 of relay NWPR, and this contact, therefore, engages contact 82. Accordingly connection is established from wire 15 to wire 81 so that on picking up of contact 77 of relay WNR the circuit for energizing the winding of the lock magnet valve device LMV is complete. This circuit is traced from wire 15 through contacts 83-82 of relay NWPR, wire 81, contacts 89-77 of relay WNR, wire 75, winding of lock magnet valve device LMV and wire 20.

As the windings of the normal and the lock magnet valve devices are now both energized, fluid under pressure is supplied to the switch motor to move the switch W from the reverse to the normal position. On movement of the switch W away from the reverse position contacts 10 and 11 are moved out of engagement with the stationary contacts 97 and 102, respectively, thereby interrupting the supply of current to the supply wires 104 and 105, while on movement of the switch W to the normal position contacts 10 and 11 are moved into engagement with the contacts 102 and 103, respectively, thereby effecting the supply of current to wires 104 and 105 of the polarity effective to cause picking up of contact 83 of relay NWPR.

Accordingly this contact of relay NWPR becomes picked up and interrupts the circuit for energizing the lock magnet valve device, and the magnet valve device LMV thereupon prevents further supply of fluid under pressure to the motor for the switch W.

The system provided by this invention is arranged so that if after the switch W has been moved to either of its positions, the contacts of the lock relay LR become released to prevent a change in the position occupied by the switch, the control relay which is energized when the lock relay contacts become released will be maintained energized to maintain the switch in the position which it occupied on release of the lock relay contacts.

If, for example, the contacts of the lock relay LR become released at a time when the winding of the normal control relay WNR is energized, the pick-up circuit for the winding of relay WNR will be interrupted by opening of the contact 55 of the relay LR. The winding of the relay WNR, however, will continue to be energized by current supplied over the stick circuit established by contact 66 of relay WNR and by contact 68 of relay WRR.

Since the winding of relay WNR continues to be energized subsequent to opening of the lock relay contacts, contact 94 of the relay WNR continues to be picked up and maintains the circuit for energizing the winding of the normal magnet device NMV so that in the event the switch W creeps from the normal position, fluid under pressure will be supplied thereto to cause return of the switch to the normal position.

Similarly, if at the time the contacts of the lock relay LR become released the winding of the reverse control relay WRR is energized, the pick-up circuit for the winding of relay WRR will be interrupted by opening of contact 64 of the lock relay LR. The winding of the relay WRR, however, will continue to be energized by current supplied over the stick circuit established by the contact 68 of relay WRR and contact 66 of relay WNR.

Since the winding of relay WRR continues to be energized subsequent to opening of the lock relay contacts, contact 98 of relay WRR is maintained picked up and maintains the circuit for energizing the winding of the reverse magnet valve device RMV so that in the event the switch W creeps from the reverse position fluid under pressure will be supplied to the switch motor to effect return of the switch to the reverse position.

The system provided by this invention is arranged so that in the event of failure of the source of current the control relay which is energized at that time will become deenergized, and will not thereafter again become energized on restoration of the source of current until a route relay is operated to establish a route control, or until an individual push button is operated.

In addition, the system is arranged so that when both control relays are deenergized, the winding of the lock magnet valve device LMV is deenergized to thereby prevent possible supply of fluid under pressure to the switch motor at a time when neither the normal nor the reverse magnet valve device is energized through its proper circuit.

For purposes of illustration it will be assumed that the failure of the source of current occurs at a time when the control relay WNR is energized and when the normal push button stick relay NPBSR and the normal route relay NRR are deenergized. At this time the normal control relay WNR is maintained energized by current supplied over its stick circuit which is established by its own contact 66 and by contact 68 of relay WRR.

As the winding of relay WNR is energized, the switch W will be in the normal position, while the contact 94 of the relay WNR will be picked up and will establish the circuit of the winding of the normal magnet valve device NMV. At this time the switch W being in the normal position the winding of relay NWPR is energized, and contact 83 of this relay is picked up with the result that even though contact 77 of relay

WNR is picked up no current is supplied to the winding of the lock magnet valve device LMV. Accordingly the lock magnet valve device LMV prevents the supply of fluid under pressure to the motor for the switch W.

On failure of the source of current the winding of the relay WNR becomes deenergized and the contacts of this relay become released. Contact 66, when released, interrupts the stick circuit for the relay winding so that on restoration of the source of current, the winding of relay WNR will not become energized by current supplied over the stick circuit for the relay winding, but will become energized only if the pick-up circuit for the relay winding is established by the normal route relay NRR or by operation of the normal push button NPB.

As the winding of relay WNR remains deenergized, the contacts of this relay remain released, and contact 77 interrupts the circuit of the winding of the lock magnet valve device LMV. The winding of the lock magnet valve device LMV, therefore, will remain deenergized and will prevent the supply of fluid under pressure to the switch motor until one or the other of the control relays is energized which will result in energization of one of the other magnet valve devices.

Since the circuit of the lock magnet valve device LMV is complete only when one of the control relays is energized, this circuit will be interrupted on release of the contacts of a control relay as a result of failure of the source of power. Accordingly if for any reason while the contacts of relay WNR remain released, the contact 83 of relay NWPR should become released, the winding of lock magnet valve device LMV will not become energized and fluid under pressure will not be supplied to the switch motor. The supply of fluid under pressure to the switch motor at this time is objectionable since neither the normal nor the reverse magnet valve device is energized.

In similar manner if the failure of the source of current occurs at a time when the reverse control relay WRR is energized, and when the reverse route relay RRR and the stick relay RPBSR are deenergized, the winding of relay WRR will become deenergized, and will not thereafter again become energized until the reverse route relay RRR or the reverse push button stick relay RPBSR becomes energized.

Under the conditions mentioned the reverse route relay WRR will be normally energized by current supplied over the stick circuit established by its own contact 68 and by contact 66 of relay WNR. At this time the switch W will be in the reverse position, while contact 98 of relay WRR will be picked up and will establish the circuit for the winding of the reverse magnet valve device RMV. As the switch W is in the reverse position, the winding of the relay RWPR is energized and its contact 90 is picked up so that contact 98 of relay WRR does not complete the circuit for the lock magnet valve device LMV.

On failure of the source of current the winding of relay WRR becomes deenergized, and contact 68 of the relay becomes released and interrupts the stick circuit for the relay winding so that on subsequent restoration of the source of current the relay winding will not again become energized and contact 68 will remain released.

On release of the contacts of relay WRR contact 78 of the relay becomes released, thereby interrupting the circuit of the winding of the lock magnet valve device LMV with the result

that even if contact 90 of relay RWPR should become released at this time as a result of the failure of the source of current, or any other reason, the circuit of the winding of the relay LMV will not be complete and current will not be supplied to this winding.

It will be seen, therefore, that the lock magnet valve device will be deenergized in the event of failure of the source of current, and will not again become energized until one or the other of the control relays is energized, which will result in energization of one of the other magnet valve devices.

In Fig. 2 of the drawings, I have shown a modified form of switch control and indication system embodying this invention. In the system shown in this figure of the drawings a switch control lever L movable between a normal and a reverse position is employed to control the circuits for energizing the normal and reverse control relays which control the motor for the switch W, while a lock stick relay LSR is provided to prevent a change in the position of the switch W when movement of the switch is not safe. The lock stick relay LSR also serves to prevent storage of switch control in the event the position of the switch control lever is altered at a time when the contacts of the lock stick relay are released.

The system shown in Fig. 2 of the drawings is similar to the system shown in Fig. 1 of the drawings and employs normal and reverse control relays WNR and WRR, respectively, and normal and reverse switch indication or switch repeating relays NWPR and RWPR, respectively. This system also includes the lock stick relay LSR. The relays WNR, WRR, NWPR, RWPR and LSR are of the type having a permanent magnet to assist in maintaining the relay armature in the release position.

The system shown in Fig. 2 of the drawings includes a switch control lever L which is movable between a normal position N and a reverse position R by an operator to effect movement of the switch W between its normal and reverse positions. The lever L has associated therewith movable contacts 130 and 131 which are movable in accordance with movement of the lever. The contact 130 is connected by wire 133 to terminal B of a battery 134, while contact 131 is connected by wire 135 to terminal C of battery 134.

When the switch control lever L is in the normal position N as shown, contact 130 engages a stationary contact 136 which is connected by wire 137 to contact 138 of lock stick relay LSR. When contact 138 of lock relay LSR is picked up, it engages a stationary contact 139 which is connected by wire 149 to one terminal of the winding of normal control relay WNR, the other terminal of which has connected thereto a branch of wire 135 leading from terminal C of battery 134.

When the lever L is in the reverse position, contact 130 engages a stationary contact 142 which is connected by wire 144 to contact 145 of relay LSR. When contact 145 is picked up, it engages a stationary contact 146 which is connected by wire 148 to one terminal of the winding of the reverse control relay WRR, the other terminal of which has a branch of wire 135 connected thereto.

It will be seen, therefore, that when the contacts of the relay LSR are picked up, a circuit is established to energize the winding of normal control relay WNR when the lever L is in the

normal position, and that when the lever L is in the reverse position, a circuit is established to energize the winding of the reverse control relay WRR.

It will be seen that when the contacts of the lock stick relay LSR are released, the switch control lever L is ineffective to establish a circuit to energize either the normal or reverse switch control relay.

The switch W has associated therewith contacts 150 and 151 which are movable in accordance with movement of the switch. The contact 150 has a branch of wire 133 leading from terminal B of battery 134 connected thereto, while contact 151 has a branch of wire 135 leading from terminal C of battery 134 connected thereto.

When the switch W is in the normal position, as shown, contact 150 engages a stationary contact 153 to which is connected supply wire 154, while contact 151 engages a stationary contact 155 to which is connected supply wire 156.

Similarly, when the switch W is in the reverse position, contact 150 engages a stationary contact 158 to which is connected a branch of supply wire 156, while contact 151 engages stationary contact 153 to which is connected supply wire 154.

It will be seen that in the normal position of the switch W the contacts 150 and 151 effect the supply of current of one relative polarity from the wires 133 and 135 to the supply wires 154 and 156, while in the reverse position of the switch W the contacts 150 and 151 effect the supply of current of the opposite or reverse relative polarity to the supply wires 154 and 156.

While the contacts 150 and 151 have been described as engaging the stationary contacts associated therewith when the switch W is in its normal or its reverse position, it should be understood that it is contemplated that these contacts may operate in the manner well-known in the art so as to engage the stationary contacts associated therewith when and only when the switch not only is in its normal or reverse position, but also is locked in that position.

The supply wire 156 is connected to one terminal of the winding of the reverse indication relay RWPR, and to one terminal of the winding of the normal indication relay NWPR. The other terminal of the winding of the relay NWPR is connected by wire 160 to contact 161 of relay WRR. The relay WRR has a movable contact 162 which when released engages contact 161, and to which is connected supply wire 154. It will be seen, therefore, that the circuit of the winding of the normal indication relay NWPR is complete when and only when the contact 162 of relay WRR is released.

The other terminal of the winding of the relay RWPR is connected by wire 164 to contact 165 of relay WNR. The relay WNR has a movable contact 166 which when released engages contact 165 and to which is connected supply wire 154. It will be seen that the circuit of the winding of the relay RWPR is complete when and only when the contact 166 of relay WNR is released.

As previously pointed out, the relays NWPR and RWPR are of a type which are responsive to current of one polarity only. The various parts of the apparatus of this system are arranged so that when the switch W is in the normal position, the contacts 150 and 151 effect the supply of current from the wires 133 and 135 to the supply wires 154 and 156 of a polarity which is effective

to cause picking up of the contacts of the relay NWPR.

Similarly, when the switch W is in the reverse position, the switch operated contacts 150 and 151 effect the supply of current from the wires 133 and 135 to the supply wires 154 and 156 of a polarity effective to cause picking up of the contacts of the reverse indication relay RWPR.

When the switch control lever L is in the normal position, as shown, contact 131 engages a stationary contact 210 which is connected by wire 211 to contact 212 of relay NWPR, while contact 212 when picked up engages a contact 214 which is connected by wire 215 to one terminal of the winding of lock stick relay LSR.

It will be seen, therefore, that when lever L is in the normal position and the contacts of relay NWPR are picked up, a circuit is established from terminal C of battery 134 to one terminal of the winding of relay LSR. This pick-up circuit is traced from terminal C of battery 134 through wire 135, lever operated contact 131, stationary contact 210, wire 211, contacts 212-214 of relay NWPR, and wire 215 to one terminal of the winding of the relay LSR.

When the switch control lever L is in the reverse position, contact 131 engages a stationary contact 217 which is connected by wire 218 to contact 220 of relay RWPR. Contact 220 when picked up engages a stationary contact 221 to which is connected a branch of wire 215 leading to one terminal of the winding of relay LSR.

It will be seen, therefore, that when the lever L is in the reverse position and the contacts of relay RWPR are picked up, a connection is established between terminal C of battery 134 and one terminal of the winding of relay LSR. This pick-up circuit is traced from terminal C of battery 134 through wire 135, contact 131, contact 217, wire 218, contacts 220-221 of relay RWPR, and wire 215 to one terminal of the winding of relay LSR.

The relay LSR has a movable contact 223 to which is connected a branch of wire 135 leading from terminal C of battery 134, while contact 223 when picked up engages a contact 225 to which is connected a branch of wire 215 leading to a terminal of the winding of the stick relay LSR. It will be seen, therefore, that when the contacts of the relay LSR become picked up, contact 223 establishes a stick circuit for the winding of the relay LSR to maintain the winding energized on interruption of either of the pick-up circuits for the relay winding.

The other terminal of the winding of the relay LSR is connected to terminal B of battery 134 by means of a circuit which is controlled by contacts 227 and 228 of locking relays, not shown. The circuits of the windings of the locking relays may be controlled in any suitable manner well-known in the art so that the contacts of these relays will be picked up when and only when it is safe to effect movement of the switch W between its two positions. It will be seen that the circuit of the winding of the lock stick relay LSR can be completed when and only when the contacts 227 and 228 are picked up, and that when these contacts are released, the winding of relay LSR is deenergized and cannot be energized by current supplied either over the pick-up circuits or over the stick circuit.

The system shown in Fig. 2 of the drawings is shown with the control lever L and the switch W in their normal positions, and with the lock stick relay LSR energized. As the lever L is in

the normal position, the winding of the normal control relay WNR is energized, and as the switch W is in the normal position, the winding of the normal indication relay NWPR is energized.

The winding of the normal control relay WNR is energized over a circuit which is traced from terminal B of battery 134 through wire 133, lever operated contact 130, contact 136, wire 137, contacts 138-139 of relay LSR, wire 140, winding of relay WNR and wire 135 to terminal C of battery 134.

The stick circuit for the winding of relay WNR is also complete and is traced from wire 133 through contacts 171-170 of relay WNR, wire 172, contacts 173-174 of relay WRR, wire 140, winding of relay WNR and wire 135.

As the winding of relay WNR is energized, the contacts of the relay are picked up and contact 198 engages contact 196 to establish the circuit to energize the winding of the normal magnet valve device NMV. The circuit for energizing this magnet valve device is traced from wire 133 through contacts 194-192 of relay RWPR, wire 191, contacts 203-201 of relay WRR, wire 200, contacts 198-196 of relay WNR, wire 195, winding of magnet valve device NMV, and wire 135.

At this time the contact 181 of relay WNR is picked up and engages contact 184 to establish connection from wire 185 to wire 180 leading to the winding of the lock magnet valve device LMV.

At this time, however, contact 168 of relay NWPR is picked up and does not establish connection from wire 133 to wire 185, and hence the winding of the lock magnet valve device LMV is not energized, and no fluid under pressure is supplied to the motor for the switch W.

At this time, as the switch W is in the normal position, the switch operated contacts 150 and 151 effect the supply of current of a polarity effective to cause picking up of the contacts of relay NWPR to the supply wires 154 and 156, while, since contact 162 of relay WRR is released, it completes the circuit for the winding of relay NWPR. The energizing circuit for the winding of relay NWPR includes wire 154, contacts 162-161 of relay WRR, wire 160, winding of relay NWPR, and wire 156. The contacts of the relay NWPR, therefore, are picked up.

As contact 212 of relay NWPR is picked up, and as the lever L is in the normal position, one pick-up circuit for the winding of relay LSR is established. This circuit is traced from terminal C of battery 134 through wire 135, contact 131, contact 210, wire 211, contacts 212-214 of relay NWPR, wire 215, winding of lock stick relay LSR, lock relay contacts 227 and 228, and wire 133 to terminal B of battery 134.

As the winding of lock stick relay LSR is energized, contact 223 of the relay is picked up and establishes the stick circuit for the relay winding.

If at this time the locking relay contact 227 or 228 should become released, the winding of the relay LSR will be deenergized and the contacts of the relay will become released. On release of contact 138 of relay LSR the pick-up circuit for the winding of relay WNR is interrupted, but the winding of this relay continues to be energized by current supplied over the stick circuit established by its own contact 170 and by contact 162 of relay WRR. Accordingly the relay winding will continue to be energized and the contacts of the relay will be picked up, and contact 198 will

maintain the circuit for the winding of the normal magnet valve device NMV.

On subsequent picking up of the locking relay contact 227 or 228 the circuit of the winding of the relay LSR will again be complete, and this winding will be initially energized by current supplied over the pick-up circuit established by contact 212 of relay NWPR, while on picking up of the relay contact 223 the stick circuit for the relay winding will again be complete.

If while the switch W is in the normal position it should creep therefrom, contacts 150 and 151 will interrupt the circuit for energizing the winding of normal indication relay NWPR, and contact 188 of this relay will become released and will establish the circuit for energizing the winding of the lock magnet valve device LMV. This valve device will thereupon effect the supply of fluid under pressure to the motor for the switch W, and since the normal magnet valve device NMV is energized, the fluid supplied to the switch motor will cause the switch W to be returned to the normal position.

When the switch W attains the normal position, contacts 150 and 151 will complete the circuit for supplying current to the supply wires 154 and 156, and the winding of relay NWPR will again be energized and its contact 188 will again become picked up. On picking up of contact 188 the winding of lock magnet valve device LMV is deenergized, and this valve device cuts off the further supply of fluid under pressure to the switch motor.

If at this time the operator desires to effect movement of the switch W from the normal to the reverse position, he may do so by moving the control lever L from the normal to the reverse position.

On movement of the control lever L away from the normal position contact 131 interrupts the previously traced pick-up circuit for the winding of the lock stick relay LSR, but this relay is maintained energized by current supplied over the stick circuit established by its own contact 223.

On movement of contact 130 out of engagement with contact 136 the previously traced pick-up circuit for the winding of relay WNR is interrupted, but the winding of this relay is maintained energized at this time by current supplied over the stick circuit established by contact 170 of relay WNR and contact 173 of relay WRR.

On movement of lever operated contact 130 into engagement with contact 142 the pick-up circuit for the winding of relay WRR is complete. This circuit is traced from terminal B of battery 134 through wire 133, contact 130, contact 142, wire 144, contacts 145-146 of relay LSR, wire 148, winding of relay WRR, and wire 135 to terminal C of battery 134.

On energization of the winding of relay WRR the contacts of this relay become picked up, and on picking up of contact 173 of the relay, the previously traced stick circuit for the winding of relay WNR is interrupted and this winding thereupon becomes deenergized, while the contacts of relay WNR become released.

On picking up of the contacts of relay WRR and release of the contacts of relay WNR a stick circuit is established for maintaining the winding of relay WRR energized. This circuit is traced from wire 133 through contacts 178-173 of relay WRR, wire 172, contacts 170-176 of relay WNR, and wire 148 to one terminal of the

winding of relay WRR, the other terminal of which is connected by wire 135 to terminal C of battery 134.

On release of the contact 198 of relay WNR the previously traced circuit for energizing the winding of normal magnet valve device NMV is interrupted, while on picking up of the contact 201 of relay WRR the circuit for energizing the winding of the reverse magnet valve device RMV is complete. This circuit is traced from wire 133 through contacts 183-186 of relay NWPR, wire 185, contacts 197-198 of relay WNR, wire 200, contacts 201-206 of relay WRR, wire 204, winding of reverse magnet valve device RMV and wire 135 to terminal C of battery 134.

At this time the winding of the relay NWPR is deenergized and its contact 188 is released since the circuit of the winding of the relay became interrupted on picking up of contact 162 of relay WRR.

On release of contact 166 of relay WNR the circuit of the winding of the relay RWPR is complete, but at this time the polarity of the current supplied through contacts 150 and 151 to the supply wires 154 and 156 is not such as to cause picking up of the contacts of relay RWPR. Instead the current supplied to the supply wires 154 and 156 is of a polarity which causes the contacts of the relay RWPR to be held in their open positions with added force.

On picking up of contact 183 of relay WRR the circuit of the winding of the lock magnet valve device LMV is complete and this valve device effects the supply of fluid under pressure to the switch motor W. As the winding of the reverse magnet valve device RMV is energized at this time, as explained above, the switch motor is operated to effect movement of the switch W from the normal to the reverse position.

The circuit for energizing the winding of the lock magnet valve device LMV is traced from wire 133 through contacts 194-192 of relay RWPR, wire 191, contacts 190-183 of relay WRR, wire 180, winding of lock magnet valve device LMV, and wire 135 to terminal C of battery 134.

When the switch W reaches the reverse position, contacts 150 and 151 effect the supply of current to the wires 154 and 156 of a polarity effective to cause picking up of the contacts of relay RWPR. On picking up of contact 194 of this relay the previously traced circuit for energizing the lock magnet valve device LMV is interrupted, and this valve device thereupon operates to prevent the further supply of fluid under pressure to the motor for the switch W.

At this time the previously traced circuit for energizing the winding of the reverse magnet valve device RMV continues to be established so that the winding of this valve device is maintained energized. Accordingly, if for any reason the switch W should creep from its reverse position with the result that the winding of relay RWPR becomes deenergized and its contact 194 becomes released so that the winding of the lock magnet valve device LMV again becomes energized, fluid under pressure will be supplied to the motor for the switch W to cause the motor to return the switch to the reverse position. When the switch again occupies the reverse position, the winding of relay RWPR will again be energized and its contact 194 will be picked up and will interrupt the circuit of the winding of the lock magnet valve device LMV which will operate to cut off the further supply of fluid under pressure to the motor for the switch W.

When contact 220 of relay RWPR is picked up, it completes a pick-up circuit for the winding of the lock stick relay LSR, but at this time this winding is already energized by current supplied over the stick circuit established by the relay contact 223.

If while the relay WRR is energized and the switch W is in the reverse position the lock stick relay LSR should become deenergized because of opening of one of the locking contacts 227 or 228, contact 145 of relay LSR will interrupt the pick-up circuit for the winding of relay WRR, but the winding of the relay WRR will continue to be energized by current supplied over the stick circuit established by contact 173 of relay WRR and by contact 170 of relay WNR.

Accordingly, the contacts of relay WRR will be maintained picked up and contact 201 will establish the circuit for energizing the winding of the reverse magnet valve device RMV, while contact 183 establishes connection from wire 191 to wire 180 leading to the winding of the lock magnet valve device LMV. As a result the winding of the lock magnet valve device LMV will be energized in the event the switch W should creep from the reverse position and cause deenergization of the relay RWPR. As the reverse magnet valve device RMV is also energized, fluid under pressure will be supplied, as explained above, to the motor for the switch W to return the switch to the reverse position.

The lock stick relay LSR operates when its contacts are released to prevent a change in the position of the switch W. When the contacts of the relay LSR are released, contact 138 interrupts the pick-up circuit of the relay WNR, while contact 145 interrupts the pick-up circuit of the relay WRR. Whichever one of the control relays is energized at the time the contacts of the lock stick relay LSR become released will be maintained energized by current supplied over the stick circuit for that relay.

Furthermore, as long as the contacts of the lock stick relay LSR remain released the other one of the control relays cannot be energized since the pick-up circuit for the winding of that relay is interrupted by the contacts of the lock stick relay. Accordingly, as long as the contacts of relay LSR remain released no change can be effected in the position of the switch.

On subsequent picking up of the contacts of the lock stick relay LSR the pick-up circuits of the control relays are again under the control of the operator, and the circuit for either of the relays may be established by operation of the switch control lever L in the manner explained above.

The lock stick relay LSR also operates to prevent storage of switch control, that is, to prevent movement of the switch W in response to movement of the switch control lever L at a time when the contacts of the lock stick relay LSR are released.

For purposes of illustration it will be assumed that the contacts of the lock stick relay LSR become released at a time when the switch control lever L and the switch W are in their normal positions, and that while the contacts of the lock stick relay LSR are released, the lever L is moved from the normal to the reverse position, after which the contacts of the relay LSR become picked up.

As the switch control lever L is assumed to be in the normal position, the winding of relay WNR will be energized, while the winding of

5 relay WRR will be deenergized. At this time the winding of the control relay WNR will be energized by current supplied over the stick circuit established by contact 170 of relay WNR and contact 173 of relay WRR.

In addition, at this time a pick-up circuit is established for the winding of the relay LSR, this circuit being traced from terminal C of battery 134 through wire 135, contact 131, contact 210, wire 211, contacts 212-214 of relay NWPR, wire 215, winding of relay LSR, locking relay contacts 227 and 228, and wire 133 to terminal B of battery 134.

The above traced pick-up circuit is interrupted, however, on opening of one of the locking contacts 227 or 228. In addition, the stick circuit which includes contact 223 of relay LSR is also interrupted, while contact 223 becomes released on deenergization of the relay winding.

On deenergization of the winding of the lock stick relay, the contacts 138 and 145 become released and contact 138 interrupts the pick-up circuit for the winding of relay WNR, but this winding is maintained energized over the previously traced stick circuit.

If the switch control lever L is now moved to the reverse position, contact 130 is moved into engagement with contact 142, but does not affect the supply of current to the winding of relay WRR since contact 145 of relay LSR is released.

In addition, on movement of the control lever L to the reverse position contact 131 is moved into engagement with contact 217, but this contact does not establish a pick-up circuit for the winding of relay LSR at this time since contact 220 of relay RWPR is released and does not establish connection from wire 218 to wire 215. The winding of relay RWPR is deenergized at this time since contact 166 of relay WNR is picked up. Furthermore, since the switch W is in the normal position, even if contact 166 of relay WNR should become released, the polarity of the current supplied to the supply wires 154 and 156 is not such as to cause picking up of the contacts of relay RWPR.

If, while the control lever L remains in the reverse position, the locking relay contact 227 or 228 which was released and which interrupted the circuit of the winding of the lock stick relay LSR should become picked up, no circuit will be established to effect energization of the winding of the relay LSR.

The stick circuit for the winding of relay LSR is interrupted since contact 223 is open, and this contact will not become picked up until the relay winding is energized by current supplied over one of the pick-up circuits.

As the control lever L is in the reverse position, contact 131 does not establish connection from wire 135 to wire 211, and hence even though contact 212 of normal indication relay NWPR is picked up, current is not supplied through this contact to the wire 215 leading to the winding of the relay LSR.

At this time contact 131 of switch control lever L establishes connection from wire 135 to wire 218, but contact 220 of relay RWPR is released, and hence current is not supplied from wire 218 to wire 215 leading to the winding of the relay LSR.

Accordingly, the winding of the relay LSR remains deenergized until the switch lever L is moved to a position of correspondence with the switch W. If the switch lever L is now moved

to the normal position, contact 131 will engage contact 210 so that a circuit is completed to energize the winding of the relay LSR, and when this winding is energized, contact 223 becomes picked up and establishes a stick circuit for the relay winding to maintain it energized until one of the locking relay contacts is subsequently released.

On this picking up of the contacts of the relay LSR the contacts 138 and 145 reestablish the pick-up circuits for the control relays WNR and WRR and the equipment is again under the control of the operator who may effect movement of the switch W in the usual manner by movement of the switch control lever L.

The system operates in a similar manner if the contacts of the relay LSR become released at a time when the control lever L and the switch W are in the reverse position, and if while the contacts of the relay LSR are released the control lever L is moved from the reverse to the normal position.

Under such circumstances neither pick-up circuit for the winding of the relay LSR will be established until the control lever L is returned to the reverse position, whereupon the winding of the relay LSR will become energized, provided the locking relay contacts are picked up, and the contacts of the relay LSR will become picked up to restore control of the switch W to the operator as previously explained.

In Fig. 3 of the drawings I have shown a modified form of system which I may employ in connection with the systems shown in Figs. 1 and 2 of the drawings to control an electric or other type of switch motor by means of a polarized relay or other device which is selectively responsive to the polarity of the current supplied thereto.

Referring to Fig. 3 of the drawings, there is shown therein a fragment of the system which includes normal and reverse control relays WNR and WRR, and normal and reverse switch indication or switch repeating relays NWPR and RWPR. The circuits of the windings of these relays may be controlled in the manner shown in Fig. 1 or 2 of the drawings, while these relays are of the type having a permanent magnet for maintaining the relay armature in its released position.

The system shown in Fig. 3, except as herein-after pointed out in detail, is the same as the corresponding systems shown in Fig. 1 or Fig. 2 of the drawings. The system shown in Fig. 3 does not have the circuits shown in Figs. 1 and 2 and controlled by the normal and reverse control relays and also by the normal and reverse indication relays for controlling energization of the windings of the magnet valve devices if such devices are employed.

The system shown in Fig. 3 includes a polarized relay X or equivalent device responsive to the polarity of the current supplied thereto to control the circuits of the switch motor, not shown, in any manner well-known in the art. As shown the relay X has a neutral contact 230 which is picked up when the relay winding is energized with current of either relative polarity. The contact 230 when picked up engages a stationary contact 231 to which is connected a control wire 232, while the contact 230 is connected by wire 234 with polar contact 235 of the relay. The polar contact 235 when in its normal position, as shown, engages normal polar contact 236 to which is connected control wire 237, while the

polar contact 235, when in the reverse position, engages reverse polar contact 238 to which is connected control wire 239.

It will be seen, therefore, that when the winding of relay X is energized with current of one relative polarity, contact 230 is picked up and connection is established from control wire 232 to wire 237, while when the relay X is energized with current of the opposite relative polarity, connection is established between wires 232 and 238. Furthermore, when the winding of the relay X is not energized, the neutral contact 230 is released and no connection is established from wire 232 to either of the other control wires. The control wires 232, 237 and 239 control the switch motor, not shown, in any suitable manner.

The normal control relay WNR has a movable contact 240 which is connected to terminal B of a suitable source of current, which may be the battery 16 employed in the system shown in Fig. 1, or the battery 134 of the system shown in Fig. 2. The relay WNR has, in addition, a contact 242 which is connected to terminal C of the same source of current.

The contact 240 when picked up engages a stationary contact 243 which is connected by wire 244 to movable contact 245 of reverse indication relay RWPR. Contact 245 when released engages a stationary contact 247 which is connected by wire 248 to contact 249 of reverse control relay WRR, while the relay WRR has a movable contact 250 which when released engages the contact 249. The contact 250 has connected thereto control wire 251 leading to one terminal of the winding of polarized relay X.

Contact 240 of relay WNR when released engages a contact 253 which is connected by wire 254 to contact 255 of normal indication relay NWPR. Contact 255 when released engages a stationary contact 257 which is connected by wire 258 to contact 260 of relay WRR. The relay WRR has a movable contact 262 to which is connected control wire 263 leading to one terminal of the winding of the polarized relay X.

The contact 242 of relay WNR when picked up engages a stationary contact 264 which is connected by wire 265 to contact 266 of relay WRR, while contact 266 is engaged by contact 262 when contact 262 is released.

The contact 242 of relay WNR when released engages a stationary contact 268 which is connected by wire 269 to contact 270 of relay WRR. The contact 250 of relay WRR when picked up engages contact 270.

It will be seen that the circuits just described are arranged so that when the contacts of normal control relay WNR are picked up, and the contacts of reverse control relay WRR and reverse indication relay RWPR are released, a circuit is established to supply current of one relative polarity from terminals B and C of the source of current to the control wires 251 and 263 leading to the winding of the polarized relay X.

The circuit from terminal B of the source of current to control wire 251 is traced through contacts 240-243 of relay WNR, wire 244, contacts 245-247 of relay RWPR, wire 248, contacts 249-250 of relay WRR, and wire 251 leading to one terminal of the winding of relay X.

The circuit from terminal C of the source of current to control wire 263 is traced through contacts 242-264 of relay WNR, wire 265, contacts 266-262 of relay WRR, and wire 263 to the other terminal of the relay X.

It will be seen that at this time the winding of the polarizer relay X is energized with current of one relative polarity, which may be considered as normal relative polarity, with the result that the relay conditions the motor, not shown, controlled thereby to effect movement of the switch to the normal position.

In addition, it will be seen that when the contacts of relay WRR are picked up and the contacts of relays WNR and NWPR are released, current of the opposite or reverse relative polarity is supplied to the control wires 251 and 263.

Under these conditions, connection is established from terminal B of the source of current to control wire 263 over a circuit which includes contacts 240—253 of relay WNR, wire 254, contacts 255—257 of relay NWPR, wire 258, and contacts 260—262 of relay WRR to control wire 263 leading to one terminal of the winding of relay X.

In addition, connection is established from terminal C of the source of current to control wire 251 over a circuit which includes contacts 242—268 of relay WNR, wire 269, contacts 270—250 of relay WRR, and wire 251 to one terminal of the winding of relay X.

It will be seen that at this time current of a different polarity is supplied to the control wires 251 and 263 with the result that the contacts of the polarized relay X effect control of the motor, not shown, for the switch W to move the switch to the reverse position.

In Fig. 4 of the drawings there is shown a modification which I may incorporate in the system shown in either Fig. 1 or Fig. 2 of the drawings to provide additional insurance that the indication relays NWPR and RWPR are energized only when it is intended that they should be energized.

In the systems shown in Figs. 1 and 2 of the drawings the supply of current from the switch operated contacts 10 and 11 to the winding of the indication relay for each position of the switch is controlled by the control relay for the other position of the switch.

Thus the circuit of the winding of the relay NWPR is controlled by a contact of the relay WRR so that this circuit is complete when and only when the contacts of relay WRR are released.

Similarly, the circuit of the winding of the relay RWPR is controlled by a contact of relay WNR so that this circuit is complete when and only when the contacts of the relay WNR are released.

The modification shown in Fig. 4 of the drawings is arranged so that the winding of the indication relay for each position of the switch will be energized only when the control relay for that position of the switch is energized, and when, in addition, the control relay for the other position of the switch is deenergized.

In the modification shown in Fig. 4 of the drawings the same reference characters are employed in the description and in the drawings as are employed in connection with the system shown in Fig. 1 of the drawings to identify the parts which are common to both systems. It should be understood, however, that the modification shown in Fig. 4 of the drawings may be incorporated in the system shown in Fig. 2, or in the modification shown in Fig. 3, as well as in the system shown in Fig. 1.

In the system shown in Fig. 4 of the drawings one terminal of the winding of the normal indi-

cation relay NWPR has a branch of supply wire 104 connected thereto, while the other terminal of the winding of the relay NWPR is connected by wire 113 to contact 112 of reverse control relay WRR. The relay WRR has a contact 108a which when released engages contact 112, and which is connected by a wire 280 to contact 107a of normal control relay WNR. Contact 107a of relay WNR when picked up engages a contact 281 to which is connected supply wire 105.

It will be seen that when the contacts of control relay WNR are picked up and the contacts of control relay WRR are released, a circuit is established from the supply wires 104 and 105 to energize the winding of the relay NWPR. This circuit is traced from wire 105 through contacts 281—107a of relay WNR, wire 280, contacts 108a—112 of relay WRR, wire 113, winding of relay NWPR, and wire 104.

It will be seen, therefore, that the winding of the relay NWPR can be energized from the supply wires 104 and 105 only when the control relay WNR is energized and when the control relay WRR is deenergized.

One terminal of the winding of the reverse indication relay RWPR has supply wire 104 connected thereto, while the other terminal of this winding is connected by wire 110 to contact 283 of relay WNR, while contact 283 is engaged by contact 107a when contact 107a is released.

The contact 108a of relay WRR when picked up engages a contact 285 to which is connected a branch of supply wire 105.

It will be seen that the winding of the relay RWPR is energized from the supply wires 104 and 105 when the contacts of relay WNR are released and the contacts of relay WRR are picked up. The circuit for energizing the winding of the relay RWPR is traced from wire 105 through contacts 285—108a of relay WRR, wire 280, contacts 107a—283 of relay WNR, wire 110, winding of relay RWPR, and wire 104.

It will be seen, therefore, that the winding of the reverse indication relay can be energized from the supply wires 104 and 105 only when the contacts of the reverse control relay WRR are picked up and the contacts of the normal control relay WNR are released.

The system shown in Fig. 1 of the drawings, when altered to incorporate the modification shown in Fig. 4, operates in substantially the same manner as the system shown in Fig. 1, and a detailed description of the operation of the system is unnecessary.

When the modification shown in Fig. 4 of the drawings is incorporated in the system shown in Fig. 2, the system as modified operates under normal conditions in the same manner as the system shown in Fig. 2, and a detailed description of the operation under normal conditions is unnecessary.

However, when the system shown in Fig. 2 is modified as taught in Fig. 4, it operates somewhat differently than the system shown in Fig. 2 in the event of failure of the source of current.

In the system shown in Fig. 2, in the event of failure of the source of current, the control relays WNR and WRR are both deenergized, and contact 166 of relay WNR establishes the circuit of the winding of relay RWPR, while contact 162 of relay WRR establishes the circuit of the winding of relay NWPR. On restoration of the source of current, therefore, the contacts of one or the other of the indication relays will become picked up, and will establish a pick-up circuit for the

winding of lock stick relay LSR so that the contacts of relay LSR will become picked up, thereby restoring the system to the condition it was in prior to the failure of the source of current.

When the system shown in Fig. 2 is modified as shown in Fig. 4, on failure of the source of current and resultant release of the contacts of both control relays WNR and WRR, the circuits of the windings of both indication relays NWPR and RWPR are interrupted and the contacts of both of these relays are released.

As a result of the failure of the source of current, the winding of the lock stick relay LSR is deenergized, and its contacts are released and interrupt the pick-up circuits for the control relays WNR and WRR, while contact 223 of relay LSR interrupts the stick circuit for the winding of relay LSR. On failure of the source of power, therefore, the contacts of the control relays interrupt the circuits of the windings of the indication relays, the contacts of the indication relays interrupt the pick-up circuits of the winding of the lock stick relay LSR, and the contacts of the relay LSR interrupt the pick-up circuits of the windings of the control relays WNR and WRR.

On subsequent restoration of the source of current all of these relays will remain deenergized unless some supplementary means is provided to energize at least one of them.

This condition can be taken care of by providing emergency means for establishing connection from terminal B of battery 134 (see Fig. 2) to wire 215 so that the winding of the relay LSR will become energized if the locking relay contacts 221 and 228 are picked up. On such energization of the winding of the relay LSR the contacts of the relay become picked up, and the pick-up circuit for one of the control relays is established, the particular one depending upon the position occupied by the switch control lever L. On energization of the winding of one of the control relays, the contacts of this relay become picked up and complete the circuit for energizing the winding of one of the indication relays, whereupon the contacts of that indication relay become picked up and complete a pick-up circuit for the winding of the lock stick relay. In addition, the stick circuit for the winding of the lock stick relay LSR is established by means of the contact 223 of the relay which becomes picked up on energization of the relay winding.

The equipment is now restored to its original condition and the operator may effect movement of the switch W in the usual manner by operation of the switch control lever L.

It may be desired to employ rectified current supplied from a commercial source of alternating current instead of direct current from a battery for normal operation of the system provided by this invention, and to provide a power-off relay operative in the event of failure of the commercial source of alternating current to establish connection from an emergency source of current, such as a battery.

A power-off relay of this type requires a short time interval for its operation, and hence there is a brief period between the failure of the normal source of current and the supply of current from the emergency source.

In order to prevent undesired release of the contacts of the control relays WNR and WRR under these conditions these relays may be made slow acting so that they will bridge over the

momentary period during transfer from one source of energy to the other.

Although I have herein shown and described only four forms of switch control and indication systems embodying my invention, it is understood that various changes and modifications may be made therein within the scope of the appended claims without departing from the spirit and scope of my invention.

Having thus described my invention, what I claim is:

1. In combination, a railway track switch movable between a normal and a reverse position, a motor for moving said switch, a normal and a reverse control relay, means for selectively energizing the winding of one or the other of said control relays, a normal and a reverse indication relay, said indication relays being of a type the contacts of which become picked up when and only when the relay winding is energized with current of a particular polarity, a pair of supply conductors through which current may be supplied to the windings of said indication relays, one of the said indication relays being arranged so that its contacts become picked up when the relay winding is energized from said conductors at a time when current of one relative polarity is supplied to said conductors, the other of said indication relays being arranged so that its contacts become picked up when the relay winding is energized from said conductors at a time when current of the opposite relative polarity is supplied to said conductors, means governed in accordance with the position occupied by the switch for supplying current of one polarity or the other to said supply conductors, a contact of the normal control relay controlling the circuit for energizing the winding of the reverse indication relay from said supply conductors, a contact of the reverse control relay controlling the circuit for energizing the winding of the normal indication relay from said supply conductors, and means controlled by said control relays and also by said indication relays for controlling said motor.

2. In combination, a railway track switch movable between a normal and a reverse position, a motor for moving said switch, a normal and a reverse control relay, means for selectively energizing the winding of one or the other of said control relays, a normal and a reverse indication relay, said indication relays being of a type the contacts of which become picked up when and only when the relay winding is energized with current of a particular polarity, a pair of supply conductors through which current may be supplied to the windings of said indication relays, one of said indication relays being arranged so that its contacts become picked up when the relay winding is energized from said conductors at a time when current of one relative polarity is supplied to said conductors, the other of said indication relays being arranged so that its contacts become picked up when the relay winding is energized from said conductors at a time when current of the opposite relative polarity is supplied to said conductors, means governed in accordance with the position occupied by the switch for supplying current of one polarity or the other to said supply conductors, the circuit for energizing the winding of each of said indication relays from said supply conductors being controlled by contacts of both of said control relays, and means controlled by said control re-

lays and also by said indication relays for controlling said motor.

3. In combination, a railway track switch movable between a normal and a reverse position, a motor for moving said switch, a normal and a reverse control relay, means for selectively energizing the winding of one or the other of said control relays, a normal and a reverse indication relay, said indication relays being of a type the contacts of which become picked up when and only when the relay winding is energized with current of a particular polarity, a pair of supply conductors through which current may be supplied to the windings of said indication relays, one of said indication relays being arranged so that its contacts become picked up when the relay winding is energized from said conductors at a time when current of one relative polarity is supplied to said conductors, the other of said indication relays being arranged so that its contacts become picked up when the relay winding is energized from said conductors at a time when current of the opposite relative polarity is supplied to said conductors, means governed in accordance with the position occupied by the switch for supplying current of one polarity or the other to said supply conductors, the circuits for energizing the winding of each of said indication relays from said supply conductors being controlled by contacts of both control relays, the circuit for energizing the winding of the normal indication relay being complete only when the contacts of the normal control relay are picked up and the contacts of the reverse control relay are released, the circuit for energizing the winding of the reverse indication relay being complete only when the contacts of the reverse control relay are picked up and the contacts of the normal indication relay are released, and means controlled by said control relays and also by said indication relays for controlling said motor.

4. In combination, a railway track switch movable between a normal and a reverse position, a fluid pressure motor for moving said switch, a lock magnet valve device operable only when energized to permit the supply of fluid under pressure to said motor, a normal magnet valve device operable when energized to control the supply of fluid by the lock magnet valve device to the motor to cause the motor to move the switch to the normal position, a reverse magnet valve device operable when energized to control the supply of fluid by the lock magnet valve device to the motor to cause the motor to move the switch to the reverse position, a normal and a reverse control relay, a normal and a reverse indication relay, means for selectively energizing one or the other of the control relays, means governed in accordance with the position of the switch and controlled by said control relays for energizing said indication relays, means operable when the normal control relay is energized and the normal indication relay is deenergized for energizing the winding of the lock magnet valve device, means operable when the reverse control relay is energized and the reverse indication relay is deenergized for also energizing the winding of the lock magnet valve device, means operable when the normal control relay is energized to energize the winding of the normal magnet valve device, and means operable when the reverse control relay is energized to energize the winding of the reverse magnet valve device.

5. In combination, a railway track switch movable between a normal and a reverse position, a

fluid pressure motor for moving said switch, a lock magnet valve device operable only when energized to permit the supply of fluid under pressure to said motor, a normal magnet valve device operable when energized to control the supply of fluid by the lock magnet valve device to the motor to cause the motor to move the switch to the normal position, a reverse magnet valve device operable when energized to control the supply of fluid by the lock magnet valve device to the motor to cause the motor to move the switch to the reverse position, a normal and a reverse control relay, a normal and a reverse indication relay, means for selectively energizing one or the other of the control relays, means governed in accordance with the position of the switch and controlled by said control relays for energizing said indication relays, means operable when the normal control relay is energized and the normal indication relay is deenergized for energizing the winding of the lock magnet valve device, means operable when the reverse control relay is energized and the reverse indication relay is deenergized for also energizing the winding of the lock magnet valve device, means controlled by both control relays and by the reverse indication relay for energizing the winding of the normal magnet valve device, and means controlled by both control relays and by the normal indication relay for energizing the winding of the reverse magnet valve device.

6. In combination, a railway track switch movable between a normal and a reverse position, a fluid pressure motor for moving said switch, a lock magnet valve device operable only when energized to permit the supply of fluid under pressure to said motor, a normal magnet valve device operable when energized to control the supply of fluid by the lock magnet valve device to the motor to cause the motor to move the switch to the normal position, a reverse magnet valve device operable when energized to control the supply of fluid by the lock magnet valve device to the motor to cause the motor to move the switch to the reverse position, a normal and a reverse control relay, a pick-up circuit and a stick circuit for each control relay for energizing the winding of such relay, means for selectively supplying current to said pick-up circuits, the stick circuit for each relay being controlled by contacts of both control relays, the stick circuit for each control relay being complete when and only when the contacts of that relay are picked up and the contacts of the other control relay are released, a lock relay governed by traffic conditions in the vicinity of the switch and controlling the pick-up circuits of both of said control relays, a normal and a reverse indication relay, means governed in accordance with the position of the switch and controlled by said control relays for energizing said indication relays, means operable when the normal control relay is energized and the normal indication relay is deenergized for energizing the winding of the lock magnet valve device, means operable when the reverse control relay is energized and the reverse indication relay is deenergized for also energizing the winding of the lock magnet valve device, means operable when the normal control relay is energized to energize the winding of the normal magnet valve device, and means operable when the reverse control relay is energized to energize the winding of the reverse magnet valve device.

7. In combination, a railway track switch movable between a normal and a reverse position, a

motor for moving said switch, a normal and a reverse control relay, means for selectively energizing the winding of one or the other of said control relays, a normal and a reverse indication relay, means governed in accordance with the position of the switch for energizing said indication relays, a polarized relay operable according as its winding is energized with current of one or the other polarity to condition the motor to move the switch to one position or the other, means operable when the normal control relay is energized provided the reverse control relay and the reverse indication relay are both deenergized for supplying the winding of the polarized relay with current of one relative polarity, and means operable when the reverse control relay is energized provided the normal control relay and the normal indication relay are both deenergized for supplying the winding of the polarized relay with current of the opposite relative polarity.

8. In combination, a railway track switch movable between a normal and a reverse position, a motor for moving said switch, a normal and a reverse control relay for controlling said motor, a pick-up and a stick circuit for each control relay for energizing the winding of that relay, control mechanism for selectively supplying current to the pick-up circuit for either of said control relays, the stick circuit for each control relay being controlled by contacts of both control relays, the stick circuit for each control relay being complete when the contacts of that relay are picked up and the contacts of the other control relay are released, a lock relay operable when its winding is energized to permit the pick-up circuits for the control relays to be established and to establish a stick circuit for energizing its own winding, a normal and a reverse indication relay, means governed in accordance with the position of the switch and also controlled by said control relays for energizing said indication relays, a pick-up circuit for energizing said lock relay winding, said circuit being controlled by said control mechanism and by one of said indication relays, another pick-up circuit for energizing said lock relay winding, said circuit being controlled by said control mechanism and by the other one of said indication relays, and means governed in accordance with traffic conditions in the vicinity of the switch and controlling the pick-up and stick circuits for energizing the lock relay winding.

9. In combination, a railway track switch movable between a normal and a reverse position, a motor for moving said switch, a normal and a reverse control relay for controlling said motor, a pick-up and a stick circuit for each control relay for energizing the winding of that relay, the stick circuit for each of said relays being controlled by contacts of both control relays, the stick circuit for each control relay being complete when the contacts of that relay are picked up and the contacts of the other control relay are released, a lock relay operable when its winding is energized to permit the pick-up circuits for the control relays to be established and to establish a stick circuit for maintaining its own winding energized, a normal and a reverse indication relay, means governed in accordance with the position of the switch and also controlled by said control relays for energizing said indication relays, a first and a second pick-up circuit for energizing the lock relay winding, said first pick-up circuit being complete only when the normal indication relay

is energized, said second pick-up circuit being complete only when the reverse indication relay is energized, a control mechanism having a normal condition in which it establishes the pick-up circuit for the first pick-up circuit.

5. circuit for the normal control relay and the first pick-up circuit for the lock relay winding, said control mechanism also having a reverse condition in which it establishes the pick-up circuit for the reverse control relay and the second pick-up circuit for the lock relay winding, and means governed in accordance with traffic conditions in the vicinity of the switch and controlling the pick-up circuits and the stick circuit for the lock relay winding.

15. 10. In combination, a railway track switch movable between a normal and a reverse position, a motor for moving said switch, a normal and a reverse control relay, a pick-up and a stick circuit for each of said control relays, a lock relay
20. governed by traffic conditions in the vicinity of the switch and controlling the pick-up circuits for both control relays, the stick circuit for each

for both control relays, the stick circuit for each control relay being independent of said lock relay and being controlled by contacts of both control relays, means for selectively establishing the pick-up circuits for said control relays, a normal and a reverse indication relay, means gov-

erned in accordance with the position occupied by the switch for energizing said indication relays, said means being operable to effectively energize the normal indication relay only in the normal position of the switch and being operable to effectively energize the reverse indication relay only in the reverse position of the switch, and means controlled by said control and

indication relays for controlling said motor.

11. In combination, a railway track switch movable between a normal and a reverse position, a fluid pressure motor for moving said switch, 40 a lock magnet valve device operable only when energized to supply fluid under pressure to said motor, a normal magnet valve device operable when energized to control the supply of fluid under pressure to the motor to cause it to move 45 the switch to its normal position, a reverse mag-

45 the switch to its normal position, a reverse magnet valve device operable when energized to control the supply of fluid under pressure to the motor to cause it to move the switch to its reverse position, a normal control relay operable
50 when picked up to establish a circuit to energize the normal magnet valve device, a reverse control relay operable when picked up to establish

55 the relay operating which picked up contacts a circuit to energize the reverse magnet valve device, a pick-up circuit for each of said control relays for supplying energy to the winding of such relay, means governed by traffic condi-

60 of said control relays being operable when picked up to establish a stick circuit to maintain itself picked up the stick circuit for each of the con-

65 picked up, the stick circuit for each of the control relays being independent of the pick-up circuit for the relay and also of the means governed by traffic conditions in the vicinity of the switch and when established is interrupted when and only when the other control relay picks up.

and only when the other control relay picks up, whereby on establishment of the pick-up circuit for either control relay and resultant picking up of such relay the relay is thereafter maintained picked up until the other control relay becomes picked up, and means governed by said control relays and by the position of the switch for energizing said lock magnet valve device.

75 12. In combination, a railway track switch

movable between a normal and a reverse position, a fluid pressure motor for moving said switch, a lock magnet valve device operable only when energized to supply fluid under pressure to said motor, a normal magnet valve device operable when energized to control the supply of fluid under pressure to the motor to cause it to move the switch to its normal position, a reverse magnet valve device operable when energized to control the supply of fluid under pressure to the motor to cause it to move the switch to its reverse position, a normal control relay operable when picked up to establish a circuit to energize the normal magnet valve device, a reverse control relay operable when picked up to establish a circuit to energize the reverse magnet valve device, a normal pick-up circuit through which energy may be supplied to the normal control relay irrespective of the condition of the reverse control relay, a reverse pick-up circuit through

which energy may be supplied to the reverse control relay irrespective of the condition of the normal control relay, means for selectively establishing said pick-up circuits, each of said control relays being operable when picked up provided the other control relay is released to establish a stick circuit to maintain itself picked up, the stick circuit for each of said control relays being independent of the pick-up circuit for the relay and when established is interrupted when and only when the other control relay picks up, whereby on establishment of the pick-up circuit for either control relay and resultant picking up of such relay the relay is thereafter maintained picked up until the other control relay is picked up, and means governed by said control relays and by the position of the switch for energizing said lock magnet valve device.
